UNITED STATES PATENT OFFICE.

GEORGE A. SANFORD, OF TIPTON COUNTY, TENNESSEE.

PLOW-DRAG.

1,131,010.

Specification of Letters Patent.

Patented Mar. 9, 1915.

Application filed July 30, 1914. Serial No. 854,103.

To all whom it may concern:

Be it known that I, GEORGE A. SANFORD, a citizen of the United States, and a resident of Tipton county, State of Tennessee, have 5 invented new and useful Improvements in Plow-Drags, of which the following is a specification.

This invention relates to attachments for plows, and more particularly to a device 10 adapted to be secured to the point of a plow for the purpose of transporting same from place to place and at the same time hold the point of the plow out of contact with the ground thus preventing the plow from fur- 15 rowing during its transportation.

Referring to the drawings—Figure 1 is a perspective view of the attachment in position on the point of a plow; Fig. 2 is a perspective view of my drag, and Fig. 3 is a 20 modified form of the invention.

In the drawings, the numeral 1 designates the base or body of the device which tapers as at 2—2, and terminates in a comparatively smaller rounded front extremity 3. 25 Central of the body, is provided a longitudinally extending slot 4, and at the rear extremity of said slot is a transverse slot 5, the front and rear walls of which are tapered as at 6 and 7 respectively. Secured by suitable 30 bolts 8 on each side of the longitudinal slot 4 is a diamond-shaped block 9, said blocks having one of their side faces or edges parallel with the side walls of the longitudinal slot. These blocks 9 are set back slightly 35 from the slot to provide a suitable space therebetween.

Secured to the front extremity of the body portion of the device by means of an eye 10 is a chain or other suitable attaching means 40 11, the free extremity of which is provided with a hook or other suitable securing means 12, while at the rear extremity the body portion is provided with a suitable wear plate 20.

In the modified form of the invention, the transverse slot 5 is dispensed with and the 45 body portion is provided only with a central longitudinal slot 15. On opposite sides of the longitudinal slot 15 and converging toward the tapered extremity of the body portion are strips 16, these strips being secured 50 to the body portion by means of bolts or the like 17.

In use the point of a plow is inserted between the blocks or strips, and wedged therein. If the plow be of the shovel type 55 the shovel is passed through the transverse slot 5, or if the plow is provided with a disk colter, the colter is received in the longitudinal slot. After this has been done, the chain at the front extremity of the body portion is fastened to any desired point of the plow, thus elevating the front extremity of the body portion. It will be seen that as the 60 plow is dragged along the ground, its point will not contact therewith, the same being 65 held in elevated position by the inclination of the body portion of the device.

I claim:

1. A device of the character described comprising a body portion provided with a 70 suitable slot, a block on either side of said slot, and spaced therefrom, and a chain carried by the front of said body portion for securing the same to a plow.

2. A device of the character described 75 comprising a body portion provided with a longitudinal slot and a transverse slot, a block on either side of said longitudinal slot, and spaced therefrom, and means for securing said body portion to a plow.

GEO. A. SANFORD.
